CLAIM

The ornamental design for a steering wheel for automobile, as shown and described herein.

DESCRIPTION

FIG. 1 is a perspective view of a steering wheel for automobile according to the present invention.

FIG. 2 is a front view of the steering wheel for automobile shown in FIG. 1.

FIG. 3 is a rear view of the steering wheel for automobile shown in FIG. 1.

FIG. 4 is a left-side view of the steering wheel for automobile shown in FIG. 1.

FIG. 5 is a right-side view of the steering wheel for automobile shown in FIG. 1.

FIG. 6 is a top plan view of the steering wheel for automobile shown in FIG. 1.

(Continued)

FIG. 7 is a bottom view of the steering wheel for automobile shown in FIG. 1; and,

FIG. 8 is a perspective view of the steering wheel for automobile of FIG. 1 showing the display of a fingerprint recognizing function drawn in broken line.

The broken lines illustrate portions of the steering wheel for automobile that form no part of the claimed design.

1 Claim, 8 Drawing Sheets
